UNITED STATES PATENT OFFICE.

JOHN M. MURPHY, OF GILMER, ILLINOIS.

WINDMILL.

SPECIFICATION forming part of Letters Patent No. 279,178, dated June 12, 1883.

Application filed October 12, 1882. (No model.)

To all whom it may concern:

Be it known that I, JOHN M. MURPHY, a citizen of the United States of America, residing at Gilmer, in the county of Lake and State of Illinois, have invented certain new and useful Improvements in Windmills, of which the following is a specification.

My invention relates to improvements in windmills; and it consists in certain peculiarities of construction, whereby a lighter and stronger machine is obtained and the tendency to travel around into the wind is obviated, substantially as hereinafter set forth in the claims.

In order to enable others skilled in the art to which my invention appertains to make and use the same, I will now proceed to describe its construction and operation, referring to the accompanying drawings, in which—

Figure 1 is a central vertical section of my windmill. Fig. 2 is a plan view of the frame carrying the rollers, and Fig. 3 is a face view of part of my wind-wheel.

A represents the frame of the tower on which my wheel is supported, and which may be of any of the usual and well-known forms. Upon the upper end of this tower is secured a circular plate or casting, B, provided with a central opening, b, and carrying on its periphery a series of anti-friction wheels or rollers, b' b', as shown in Figs. 1 and 2.

C represents the turn-table, cast with upper and lower peripheral flanges, c c', and a downwardly-projecting central hub, C', which enters the opening b in the plate B, as seen in Fig. 1. This hub acts as a center upon which the turn-table revolves, and the anti-friction wheels b' b' on the plate or cap B travel between the flanges c c' of the turn-table and hold it perfectly steady, preventing it tipping in any direction, or at any time jumping from its seat, while no bolts or screws are used for this purpose, which are at all times liable to break or jar loose.

On one side the turn-table C is on its upper face formed with a projection, C², which forms a bearing for the shaft D, upon which the wind-wheel is secured. On the same side, and in line with the projection C², is a barrel, C³, through which the shaft D passes, and upon the outer end of this shaft is secured a socketed casting, E, from which radiate the arms

E' of the wheel. Upon the outer ends of these arms E' is secured a ring, F, cast in sections, having flanged ends, which clasp the arms E', and are bolted together, as seen at f f, Fig. 3. 55 The sections of this rim or ring F are formed with transverse lugs or projections f' and a longitudinal flange, f'', the purpose of which will be presently seen. The sections of the ring F are perforated close to the lugs f' and 60 flange f'', and in each of these perforations is screwed a metal rod or tube, G, which form the arms upon which the fans H are hinged by straps h on their rear sides. The arms or rods G, if simply screwed into the ring F, would be 65 very liable to break out, but, being braced by the lugs f' and flange f'' in the direction of the greatest strain, are held firmly in place and make a very light but strongly-constructed wheel. 70

The fan-blades H are hinged upon the rods or tubing G, preferably at one side of their center, and are each provided with an eye, h', to which is secured a link or hook, l, connected at its rear end to a ring, I, of metal, as seen in 75 Fig. 1. This ring is supported on arms I', secured in a hub, I², revolving with the wheel and sliding horizontally on the barrel C³, and by connecting this hub with the governor generally used on this class of wheels the speed of 80 the wheel in varying winds may be easily regulated.

The inner end of the shaft D is provided with a beveled-gear wheel, d, and to the projection C² over the said shaft is bolted an arm, D', forming the bearing for the upper end of a shaft, L, carrying a bevel-gear, L', meshing with the gear d. This shaft passes downward through the hollow hub C' of the turn-table, and is here surrounded by a hollow shaft, M, carrying on 90 its upper end a bevel-gear, M', also meshing with the gear d. The shafts pass downward a short distance, and are supported by cross-bars of the frame of the tower. They carry on their lower ends, connected by ratchets m i 95 and pawls m' i', the bevel-gears M² L², both meshing with a pinion, N, on the end of a shaft, N', journaled in the frame of the tower, and supplied with a chain or belt wheel, n, for driving machinery, and a wrist-pin, n', for 100 connection with a pump.

In all windmills using a single bevel-gear-

ing for communicating motion from the wheel to the machinery there is a tendency on the part of the wheel to travel around out of the wind; but by using a double gearing, as I have shown, with shafts revolving in opposite direction, this tendency is counteracted, while the ratchets and pawls allow of any change of position rendered necessary by a change in the direction of the wind. The ratchet-and-pawl devices may as readily be used on the upper as the lower set of gearing.

Having thus fully described my invention, what I claim as new, and desire to secure by Letters Patent, is—

15. 1. In a wind-wheel, the ring F, cast in sections, as described, and provided with the transverse lugs f' and longitudinal flange f'' , substantially as and for the purpose set forth.

2. The combination, in a wind-wheel, of the ring F, cast in sections, as described, and provided with the lugs f' and flange f'' , with the rods or tubes G, carrying the swiveled or hinged fan-blades H, substantially as and for the purpose set forth.

3. The turn-table C, having a central hub, 25 C', peripheral flanges $c'c'$, and projection bearing C², and barrel C³, all cast in one piece, substantially as shown and described.

4. The combination of the plate B, having central opening, b, and friction-rollers b', the turn-table C, provided with flanges $c'c'$, and having hub C', projecting bearing C², and barrel C³, shaft D, carrying gear d, wind-wheel E, having arms E', the sectional ring F, having lugs f' and flange f'' , the pivoted fans H, controlling wheel or ring I I', shafts L M, gears L' M' L² M², and the shaft N', having pinion N and chain-wheel n, all substantially as shown and described.

In testimony whereof I affix my signature in presence of two witnesses.

JOHN M. MURPHY.

Witnesses:

HARRY HARRISON,
FRANK JOHNSON.
